Joseph F. O'Brien
ATTORNEY

UNITED STATES PATENT OFFICE.

NATHAN NAMAN, OF NEW YORK, N. Y., ASSIGNOR OF ONE-HALF TO PHILIP MONKA.

SHADE ROLLER.

Application filed April 2, 1926. Serial No. 99,231.

This invention relates to improvements in shade rollers.

One of the objects of this invention is to enable a shade roller of the spring-actuated type to be stopped and started more positively and accurately.

Another object of the invention is to provide in a shade roller, a pawl and ratchet device which, while providing a secure and positive automatic locking during unwinding movement of the shade so that a mere stopping of such unwinding movement will cause a retention of the shade in the position to which it is moved and at which manual pressure is released, will, furthermore, provide for a ready release of the locking engagement of the pawl to permit a winding movement of the shade by the spring.

Another object of the invention is to provide locking means which will compensate for disalignment or improper mounting of the operating spindle either through wear or play in the mounting slot of the bracket or through failure to position the bracket in proper position on the window frame.

With these and other objects in view, the invention comprises the combination of members and arrangement of parts so combined as to co-act and cooperate with each other in the performance of the functions and the accomplishment of the results herein contemplated, and comprises in one of its adaptations the species or preferred form illustrated in the accompanying drawings, in which:—

Fig. 1 is a vertical section, partly in elevation, of a shade roller embodying my invention;

Fig. 2 is an end elevation of the shade roller shown in Fig. 1;

Fig. 3 is a section on the line 3—3 of Fig. 1 looking in the direction of the arrow; and

Fig. 4 is a perspective view of the operating section of the shaft or spindle.

Referring now to these drawings which illustrate a preferred embodiment of my invention, 1 indicates a shade roller which is of the conventional type and is provided with a spindle 2 surrounded by a spiral spring 3 anchored to the roller and spindle in the usual way. As shown, the spindle or shaft 2 has a metallic section 4 provided with a bearing collar 4^a adapted to fit within a bearing 5^a in a metal cap 5 at the end of the shade roller and also having a ratchet wheel 6 and a squared mounting end 7 which is adapted to

fit within a slot 8^a in a bracket 9 connected to a wall 10 by nails 11.

It is desirable, in mounting a shade roller, to use one-piece brackets of the type shown in which the mounting slot 8^a extends at an inclination from the vertical axis of the bracket and the upper end 12 thereof communicates with a side entrance opening 13 so as to enable a ready insertion of the squared mounting part 7 through the said entrance opening 13. It is intended that brackets 9 of this type be placed on the window frame at a slight inclination so as to cause the slot 8^a and the squared operating end to be positioned vertically. As these brackets, however, are attached to the walls by unskilled persons, the brackets 9 are often placed in vertical position and the slots 8^a are, therefore, inclined to the vertical. This disalignment usually causes considerable trouble in the operation of the conventional shade roller, which is provided with a ratchet wheel having only two oppositely-arranged notches which in order to permit one of the gravity pawls to fall into the same, must be arranged in a vertical plane substantially passing through the axis of the ratchet wheel, it being desirable to have a free space between these oppositely-arranged notches in order to enable ready release of the pawl when it is desired to permit upward spring-actuated winding movement of the shade. It is, therefore, inadvisable to use a pawl with a series of teeth surrounding the entire circumference, because in such event, the pawl keeps dropping in between the teeth and prevents ready release for upward or winding movement of the shade.

By the use of my invention, I am enabled, however, not only to provide the free inter-notch space necessary for the positive release of the pawl to procure a good winding movement but am also enabled to procure a more positive automatic stopping of the roller at any point and to compensate for any disalignment from the vertical of the operating or mounting part of the spindle, the position of which with relation to the vertical, will determine the position at which the gravity pawl will contact the ratchet wheel. In order to accomplish this, I preferably provide two pairs of notches 14, 14^a and 15, 15^a on the ratchet wheel, one pair at each end of the squared mounting portion of the spindle, one member of each pair extending on oppo-

site sides of the vertical axis of said operating end or of vertical position in which the gravity pawl moves, thus enabling a dropping of the pawl into one of such notches and compensating for any inclination from the vertical of the mounting of the squared mounting end bracket.

It will be seen that when a pair of notches are so disposed in relation to the mounting end, one of the members of each pair will extend to one side and the other member to the opposite side of a vertical plane passing through the axis of the ratchet wheel and that in view of this arrangement, one of the pawls, when the movement of the shade roller is stopped or slowed up, will drop in a substantially vertical direction and into contact with the ratchet wheel. When a pair of notches are so disposed the pawl will drop into one of these notches. The placing of the notches in this position will, therefore, compensate for any disalignment from a vertical plane of the squared mounting end of the stationary spindle and, furthermore, the arcuate, unbroken surfaces 6^a, 6^b, on opposite sides of these notches will enable the full disengagement of the pawl in order to get a proper start for the spring-actuated winding-up movement of the roller.

The opposite end of the roller is provided with the usual cylindrical stub spindle 18 which is mounted in a bracket 19 attached to the wall 20.

Having described my invention, I claim:—

1. A shade roller provided with a station-

ary spindle and a spiral spring arranged between said roller and spindle to cause a winding movement of the roller, a gravity pawl pivotally mounted on one end of the roller, a ratchet wheel fixed on the spindle and provided in its circumference with a pair of notches arranged closely adjacent to each other within a quadrant section of said circumference, the members of which pair extend to opposite sides of a vertical plane passing through the axis of said wheel, said wheel having arcuate unbroken circumferential surfaces on opposite sides of said notches.

2. A shade roller provided with a stationary spindle and a spiral spring arranged between said roller and spindle to cause a winding movement of the roller, said spindle being provided with a squared mounting end and having a ratchet wheel also fixed thereon and provided at each of the opposite sides of said squared mounting end with a pair of notches, the members of each pair of notches being arranged closely adjacent to each other within a quadrant section of the circumference of said wheel and having between the pairs arcuate unbroken circumferential surfaces, and said members of a pair being arranged on opposite sides of the vertical axis of said squared mounting end, and a gravity pawl mounted on the end of said roller.

In witness whereof, I have signed my name to the foregoing specification.

NATHAN NAMAN.
